UNITED STATES PATENT OFFICE.

DAVID LEETE KANE, OF CINCINNATI, OHIO.

RULE.

1,130,610.

Specification of Letters Patent.

Patented Mar. 2, 1915.

Application filed July 28, 1914. Serial No. 853,753.

To all whom it may concern:

Be it known that I, DAVID LEETE KANE, a citizen of the United States, residing at Oakley, Cincinnati, in the county of Hamilton and State of Ohio, have invented new and useful Improvements in Rules, of which the following is a specification.

This invention relates to rules and level devices such as are used by bricklayers, masons, and like artisans, the primary object being to provide a device of this character which is sectional in construction whereby the sections may be separated and stored conveniently in a tool-box, or the like for the purpose of transportation.

A further object of the invention is to provide a sectional rule whose sections are constructed so that they may be joined securely and in true alignment with each other.

20 A still further object is to provide a rule of this nature whose sections are each composed of a body of soft wood or the like, and facing strips therefor which are constructed of hard wood, or other durable material.

25 The invention consists in the features of construction, combination, and arrangement of parts, hereinafter fully described and claimed, reference being had to the accompanying drawings, in which:

30 Figure 1 is a fragmentary side elevation of the device; Fig. 2 is a transverse sectional view on line 2—2 of Fig. 1; Fig. 3 is a longitudinal sectional view on line 3—3 of Fig. 2; Fig. 4 is a similar sectional view on line 4—4 of Fig. 2; Fig. 5 is a vertical sectional view on line 5—5 of Fig. 2; Fig. 6 is a perspective view of the joint end of one rule section; and, Fig. 7 is a similar view of the said section end looking at the same from 40 the opposite side.

Referring to the drawings, it will be seen that the body of the rule is divided into three sections, which include the terminal sections 1 and 2 and the intermediate section 3, each of which includes a body portion 4 which is constructed of some soft and inexpensive wood, or the like. Facing strips 5 of hard wood are secured in suitable manner to the upper and lower edges of the body of the intermediate section and terminate in spaced relation to the ends thereof with the beveled faces 6.

Each terminal section is provided in its inner end, and the intermediate section in 55 each of its ends, with a longitudinally taper-

ing dove-tailed recess 7 equal in depth to one-half the thickness of the body and opening through its end face and one side face thereof. A longitudinally tapering and dove-tailed tongue 9 is formed upon each of these section ends in prolongation of the inner wall of the corresponding recess for reception within the recess 7 of the adjacent section end, the tongue of the latter section being adapted to fit within the socket of the first section. The end face 9 of each tongue is inclined correspondingly with the inner end wall 10 of the receiving recess of the coacting section, whereby the joint will be rendered more secure when the sections are 70 united. In order to strengthen the joint further, the end faces of the body of each section above and below its recess are inclined, as at 11, and the adjacent faces above and below the tongue are correspondingly 75 inclined as at 12, in parallel relation to the faces 11, whereby a vertical, longitudinally extending shoulder 13 is formed between the same to resist lateral, relative movement of the joined section ends. Transverse openings 14 are provided in the tongue and in the inner wall of the recess of each section end, which are adapted to align with similar openings in the interlocking parts of the 80 coacting section end for the reception of the connecting bolt members 15, which in this instance are shown to be of the type commonly known as "saw handle screws", in order that there will be no outwardly projecting ends, the heads thereof being countersunk in the outer side faces of the body 85 portions of the respective sections.

At each joint between the sections, detachable facing strip sections 16 are fitted against the upper and lower edges of the meeting ends in staggered relation to the joint and have their ends beveled correspondingly to the ends 6 of the permanently connected facing strip sections for even engagement, therewith. These detachable sections extend to the outer ends of the terminal sections of the rule body, and are adapted to be connected at their opposite ends to the respective section ends of the rule by means of the vertical securing bolts 17, 100 which are mounted within the openings 18 105 therein.

As shown in the drawings, the terminal sections of the rule are provided preferably with spirit tubes 19 which are arranged at 110

right angles to the longitudinal axis of the rule and are thus adapted for use in planing vertical surfaces. A longitudinally extending spirit tube 20 is provided medially within 5 in the intermediate section for use in leveling horizontal surfaces.

From the foregoing description, taken in connection with the accompanying drawings, it should be apparent that I have provided a combined rule and level device which is adapted to be manufactured cheaply, and is composed of detachable sections which may be joined together in such a manner as to provide a body whose straight edges are 15 in true alinement and uninterrupted. When the sections are disconnected, they may be stored conveniently in a minimum amount of space, whereby the transportation of the device in the ordinary tool-kit from place to place, as is often found desirable in practice, will be facilitated.

The main features of the construction are the provision of separable sections, each of which includes a body that may be constructed of soft wood or the like material, and hardwood facing strips therefor, and the specific form of interlocking joint between the sections. It is to be understood, however, that minor changes in the details 30 of construction, such as fall within the scope

of the appended claim, may be resorted to in practice whenever necessary.

What is claimed is:

A rule of the class described comprising an elongated body including separable sections, one end of each section being provided with a longitudinally tapering dove-tailed recess opening through one of its side faces, a longitudinally tapering dove-tailed projection formed upon the said end of each 35 section in prolongation of the inner wall of the recess for reception within the recess of the companion section when the sections are united, and means for securing the tongue of one section end detachably within the 40 recess of the other section end, the joint end of each section being provided above and below its recess and tongue respectively with parallel, longitudinally inclined faces forming shoulders therebetween adapted to 45 interlock with the corresponding shoulders of the coacting joint end of the adjacent section.

In testimony whereof I affix my signature in presence of two witnesses.

DAVID LEETE KANE.
